(57) CLAIM

The ornamental design for a shoe, as shown.

DESCRIPTION

FIG. 1 is a left side elevational view of a shoe embodying our new design.

FIG. 2 is a right side elevational view thereof; and,

FIG. 3 is a top plan view thereof.

The claimed design comprises the stripes on the top and sides of a shoe. The shoe itself, shown in broken lines, forms no part of the claimed design.
